APPARATUS FOR COMPACTING AND SURFACING PLASTIC MATERIAL

Robert William Baily, Philadelphia, Pa.

Application August 17, 1933, Serial No. 685,590

4 Claims. (Cl. 94—48)

One object of my invention is to provide a method and apparatus for compacting concrete which may be initially harsh and unworkable but becomes plastic under vibration before any initial 5 set has developed therein by an apparatus consisting of vibrating screeds and planers.

A further object is to provide a sectional screed, the parts of which are individually adjustable for forming a composite screed, the adjustment providing for fitting the screed to various desired contours, such as the transverse contour of a pavement or the like, it being particularly applicable for roadways, although it can be used for floors and the like.

15 A further object is to provide a method for vibrating the concrete in a roadway or the like for causing it to become dense and homogeneous by ridding it of entrapped air and water, vibrating screeds being used for this purpose which 20 strike off the surface to the approximate contour desired, the screeds being controllable either to rectify the surface of the roadway into a true straight line or to make its surface conform to a predetermined convex or concave requirement, 25 the sections of the screeds having each a vibrator so that all the sections are vibrated and yet can be adjusted for a change in contour as desired.

Still a further object is to provide a screed for forming a concave or convex surface which consists of a plurality of screed sections, each having a straight or adjustably curved surface and each being adjustable with relation to a carrying frame and with relation to each other, so that in the case of the straight sections, a plurality 35 of plane surfaces can be formed on the concrete at angles to each other to make approximately a curved surface.

My invention also contemplates the combination of the screed sections mentioned with a reciprocating planer following the screed sections to 40 reduce the surface of the concrete to the desired trueness and smoothness without humps or depressions.

The method and apparatus for the use of and 45 the design of the vibrating screeds are shown in my copending applications Serial Numbers 428, 747 and 514,124. The apparatus for supporting the screeds and determining their positions is shown in my copending application Serial Number 576,727 issued as Patent Number 2,018,294, on October 14, 1935. One form of the vibrators is shown in my Patent No. 1,876,271.

50 My invention comprises a method and apparatus for vibrating the concrete of a roadway 55 while it is in plastic condition and also striking

off the surface to approximate contour and then, planing it to the exact desired contour, thus leaving the concrete dense and homogeneous, free from entrapped air and water and its surface true to the desired contour.

A further object is to provide the apparatus easily and quickly adjustable to desired changes in the contour and which further is capable of constructing single slabs that are too wide for 5 vibrating screeds heretofore known.

Still a further object is to provide an apparatus in which a preliminary strike-off planer is followed by vibrating screeds and then by a finishing planer, whereby striking off the surplus concrete from the surface of the freshly laid pavement is done by the strike-off planer rather than 10 the vibrating screeds.

With these and other objects in view, my invention consists in the construction, arrangement and combination of the various parts of my apparatus and in the practice of my method, whereby the objects contemplated are attained, as hereinafter more fully set forth, pointed out in my claims, and illustrated in the accompanying drawings, in which:

Figure 1 is a rear elevation of a vibrating sectional screed embodying my invention.

Figure 1A is a view of the left end of Figure 1 showing a modified construction.

Figure 2 is a plan view of the same, a portion 30 of the upper framework thereof, as indicated by the bracket 2a, being broken away.

Figure 3 is an end elevation of the screed apparatus shown in Figures 1 and 2 showing one form of advancing means for the apparatus.

Figure 4 is a sectional view on the line 4—4 of Figure 1.

Figure 5 is a diagrammatic end elevation showing another form of advancing means.

Figure 6 is a rear elevation somewhat similar 40 to the left end of Figure 1 showing a modified embodiment of the invention.

Figure 7 is a diagrammatic end elevation of a vibrating screed, such as shown in Figure 1, followed by a planer.

Figure 8 is a diagrammatic plan view of the same.

Figure 9 is a rear elevation of the planer showing it diagrammatically.

Figure 10 is a diagrammatic plan view of a 50 modified form in which the planer is made in two sections.

Figure 11 is a rear elevation showing the planer of Figure 10 diagrammatically.

Figure 12 is a rear elevation showing a means 55

for providing a screed section of adjustable curvature.

Figure 13 is a diagrammatic end elevation showing a planer drawn by a screed, such as the kind illustrated in Figure 6, rather than by a framework for the screed and planer as in Figure 7.

Figure 14 is a diagrammatic view of a planer with vibrating means thereon.

10 Figure 15 is a diagrammatic plan view showing staggered screeds rather than aligned screeds; and Figure 16 is a diagrammatic plan view showing a strike-off planer, vibrating screeds and a finishing planer successively arranged.

15 In Figure 1, concrete 10 is illustrated between side forms 12 and the concrete is being compacted by screed sections 14, 14a, and 14b. The screed sections are board or plank-like devices and they may or may not be flexibly connected together, as by hinges 16. They are preferably provided along their forward edges with upstanding flanges 18 which prevent concrete from surging up over their forward edges and onto their top surfaces.

20 25 The sections 14, 14a, and 14b are preferably mounted so that they can be adjusted, although they may be permanently mounted in a position for forming a predetermined contour of roadway if desired. I have illustrated them as being mounted by means of brackets 20, yokes 22, connecting elements 24, such as shown in my Patent Number 2,018,294, and posts 26. The posts 26 are carried by a cross bar 28 of a carriage which has end frame members 30 and wheels 32. The 30 35 wheels 32 travel on the side forms 12. Figure 1A shows a means for adjusting the frame vertically with respect to the carriage.

The elements 24 are elastic belts of considerable width, as shown at the left end of Figure 2, 40 and encircling pins 34 and 36 of the brackets 20 and yokes 22 respectively. The posts 26 are threaded rods provided with lock nuts 38 for vertically adjusting the posts relative to the cross bar 28 and retaining such adjustment.

45 50 On each screed, I mount casings 40 and journal shafts 42 therein. The shafts have offcenter weights 44 within the casings 40 for imparting vibrations to the screed sections 14, 14a, and 14b upon rotation of the shafts. The shafts are connected together by flexible couplers 46 so that they may be simultaneously operated instead of having to provide a separate power means for each one, although separate power means could be provided if desired. The couplers 46 permit 55 the screed sections 14, 14a, and 14b to be bowed up or down as desired.

I have shown as a means for rotating the shafts 42, an engine 48 mounted on a bracket 50. The bracket 50 in turn is mounted on a bracket 52 60 on the cross bar 28, flexible belts 54 and pins 56 being provided for mounting the brackets relative to each other.

65 By means of flexible couplers 58, the engine 48 is connected with shafts 60. One of the shafts 60 is belted by a belt 62 to the shaft 42 on the screed section 14.

70 From the foregoing construction, it is obvious that the screed comprising the screed sections and the engine 48 are elastically mounted so that the transmission of vibrations thereof to the carriage frame is minimized.

75 Various means may be provided for propelling the carriage frame and consequently the screed along the concrete 10. I have shown winding drums 64 in Figures 1, 2, and 3 having cables 66

looped therearound and then extending under pulleys 68 to stakes 70 driven ahead of and behind the carriage frame. The operation of the drums 64 is controlled by clutches 65 which connect and disconnect the shafts 60 and counter-shafts 67 with relation to each other and which are controlled by clutch levers 69. The stakes 70 can be driven a considerable distance apart and changed from time to time as the machine progresses along the pavement.

10 In Figure 5, I have shown another arrangement wherein the wheels 32 are operatively connected together by a chain or belt 72 and connected with a counter-shaft 74 by a chain or belt 76, the counter-shaft to be driven at a suitable low speed by means of gearing or the like from the engine 48.

15 Means is provided for moving the screed sections 14, 14a and 14b forwardly without depending on the posts 26 for this purpose. This means 20 consists of a cross bar 78 and flexible elements, such as chains 80 connected therewith and with the screed sections. Plows or deflectors 82 may be mounted on the forward edges of the screed sections 14a and 14b to force surplus concrete 25 away from the side forms 12 and toward the center of the roadway.

25 In Figure 7, I have shown in addition to the screed sections, a planer A following the screed. The carriage frame is a little different in shape, 30 but operates the same as in the previous figures and consequently it, as well as other parts corresponding to those in the previous figures, will be given the same reference numerals. The planer consists of a blade 84 having a front plate or 35 flange 86 to carry ahead surplus concrete that may accumulate in front of the planer.

The planer may be supported by flexible elements 88 such as chains which are connected to a subcarriage frame 90 having wheels 92 to travel 40 on the side forms 12 following the wheels 32. The flexible elements 88 are preferably connected with some raising device, such as a bell crank lever 94 pivoted to a bracket 96 of the frame 90. In Figure 7, the bell crank lever 94 is shown extended rearwardly. It can be swung a half revolution clockwise about its pivot to the bracket 96 which will elevate the planer A, the elements 88 passing overcenter with respect to the pivot of the lever 94, which will lock the planer in its 50 elevated position. Any other device may be used to accomplish this purpose.

The planer A may be propelled by flexible elements 98 extending to the carriage frame 30 or a suitable cross bar thereon, such as indicated 55 at 100 in Figure 8.

Other suitable means can be used for supporting and propelling the planer A, as desired.

In Figure 12, I have shown diagrammatically how either one of the screed elements 14 or the planer A can be adjusted to vary its contour so that in the case of the screed sections, each may be warped to an arc of the desired radius to strike off a truly convex surface on the concrete 10 or to adjust the planer A to fit pavements of any 60 desired convexity or concavity. The ends of the screed section or planer are rigidly connected with a frame member 102, while the central part of the screed section or planer may be raised or lowered by a jack screw 104. The front flange 70 75 of the planer may be provided with deflecting portions 87 to prevent the planer from pushing the surplus concrete in front of it over the side forms 12.

The planer A is preferably longer than the 75

distance between the opposite side forms 12 so that it projects therebeyond as clearly shown in Figure 8. It may rest thereon whereby they act as a surfacing gauge for it, or may be hung in predetermined elevation with respect to the wheels 32 and 92 and supported thereby a predetermined distance above the side forms. The planer may be of nonreciprocating type if desired, although it is preferably of the reciprocatory type which will now be described.

Reciprocations of the planer A are preferably in a transverse direction with respect to the forward movement of the planer whereby to saw off or scrape the surface of the concrete 10, thereby assisting in the finishing and polishing of the surface of the concrete by a trowelling action. To obtain this reciprocating action, the planer may be mechanically operated in several different ways. In Figure 9 for instance, I have shown an engine 48a driving a crank disk 106, to the crank pin of which, one end of a pitman 108 is connected. The other end of the pitman is pivoted to the planer. The engine 48a may be provided especially for the planer, or the crank disk 106 may be operatively connected with the engine 48 which operates the vibrators for the screed sections.

In Figure 10, I have shown a modified form of planer consisting of sections 84a and 84b provided with front flanges 86a and 86b and deflector portions 81a and 81b. The sections 84a and 84b are telescopically associated with each other, for instance by means of hooked flanges 110 on one section engaging the edges of the blade and front flange of the other section. The two sections are made to reciprocate in opposite directions, for instance by a crank shaft 112 journalled on one section and connected by a pitman 114 to the other section.

The crank shaft 112 is connected by suitable means, such as universal joints 116 and bevel gears 118, to the engine 48. Suitable clutches of course can be provided for the planers, but it has not been deemed necessary to illustrate these on the drawings.

In Figure 11, the overlapping planer sections 84a and 84b would apparently leave a considerable ridge at the right hand end of the section 84a. In practice however, the thickness of the section 84a with respect to the size of the roadway is considerably small and such a ridge would be practically imperceptible, it being exaggerated on the drawings because of the scale necessary in order to properly show the invention.

By the reciprocating arrangement of two planer sections, as in Figure 10, and the sections alternately approaching and receding from each other, the effect of friction of the concrete on the planer, as in Figure 9, is neutralized so that there is not the marked tendency of the supporting frame 90 to shift transversely one way and then the other during the reciprocations of the planer.

In Figure 6, I show how a cross member 28a may be supported on the vibrating screeds 14a and 14b instead of on the wheels 32. In this construction it is unnecessary to have any supporting frame and the end screed sections 14a and 14b may extend over the side forms 12 and rest thereon as illustrated.

When a planer is used with this type of screed, it can be drawn as in Figure 13 by its draft chains 98a connected directly with the screed.

As the apparatus is propelled over the concrete 10, one end of the screed may be advanced ahead of the other when there is any tendency for the

concrete to be high on one side of the roadway and low on the other. This will serve to shift the concrete in the opposite direction to keep the quantity piled up in front of the screed evenly distributed transversely of the roadway.

In Figure 15, I have shown how the screed sections may be arranged in staggered relation and the path of one may overlap the path of the other so there will not be any unvibrated strip of concrete between the paths of the screed sections.

In Figure 16, I show a strike-off planer 116 ahead of the vibrating screed sections 14, 14a, and 14b. This planer does the work of striking off the majority of the surplus concrete above the finish line, making it easier for the screed to operate without having to do this job and the trueness of the finished pavement is thereby improved.

Sometimes it is desirable to raise the screeds so that the machine can be run backwardly over the vibrated concrete and then lowered for a second vibrating application. This can be accomplished by elevating the frame member 28 relative to the carriage wheels 32. In Figure 1A, I show one way in which this can be done. An upright 30a extending from the wheels 32 is received in a socket member 30b secured to the frame member 28. A set screw 30c can be manipulated for raising the frame member 28 relative to the wheel 32 for thus bodily raising the screed above the surface of the concrete 10. The screw 30c, when rotated in an opposite direction, lowers the screed or planer, as the case may be, and its height with respect to the carriage frame can also be adjusted by the set screw.

The foregoing described apparatus is especially adapted for the method of compacting and surfacing plastic materials used for the construction of roadways. I have found that in such construction it is necessary to adjust the screed to conform to the crown of the roadway cross section. In some cases, these adjustments must be frequently made, due either to the transverse contour of the roadway changing from time to time as it does at intersections with other roadways, or because the screed itself or the carriage supporting the screed bends or deflects due to changes in its weight or the effective weight of the supported members, or due to variations in the resistance of the concrete to manipulation as the proportion of mixing water varies or as the harshness of the aggregates changes.

I have shown one way in which each end of each screed section may be vertically adjusted, although mechanical equivalent adjusting means of faster operating characteristics can be used as desired.

Because the vibrating screeds must be exceedingly stiff to prevent distortion induced by the violent action of the vibrators, it is difficult if not impossible to arrange a long screed so that changes in its longitudinal vertical curvature may quickly and conveniently be made.

When the concrete slab being constructed is exceedingly wide, it is inconvenient to construct and operate a single screed capable of attending to the entire width in one member and further it is convenient when constructing a concrete slab having a vertical transverse curvature either convex or concave, to average the curve or divide it into a series of tangents, or into a series of curves, so that the surface remaining after the passage of the vibrating screeds which formed

such tangents or curves may be planed off or trowelled to the desired true curve or tangent with the minimum of labor and skill.

The labor and skill required to produce the desired true curve or tangent may be further reduced if a reciprocating planer having the true curvature or tangent of the pavement, be made to follow immediately behind the vibrating screeds to reduce the surface of the concrete to the desired curvature or tangency.

The vibrating screed which I disclose reduces what are otherwise harsh and unworkable concrete mixtures to a plastic and flowing substance, with the result that if any considerable amount of concrete collects and piles up in front of the vibrating screed, its hydrostatic pressure will cause it to flow under and beneath the screed and rise or surge up therebehind, resulting in the surface of the following concrete being considerably above the desired elevation. It then becomes necessary to plane the surface off to the desired elevation. I have discovered that where the amount of concrete in front of the vibrating screed may appear to be sufficient, but where on the other hand, due to its porosity and where, due to the elimination of the porosity by the effect of the vibrating screed, the surface of the concrete in places is below the desired elevation, these depressions may easily and thoroughly be filled and brought up to proper grade and contour by the excess of concrete being carried along by the planer following the screed.

It is my intention to cover by my claims, such modifications of the apparatus or variations in the practice of the method which may be considered as falling within their scope.

I claim as my invention:

1. In an apparatus of the character described, a carriage frame, a plurality of screed sections carried thereby and extending transversely relative to the direction of travel of the carriage frame, means for individually adjusting the height of each end of each screed section, means for circularly vibrating each screed section, a planer following said screed sections and means for vibrating said planer, said planer being curved and the curvature thereof being adjustable.

2. In apparatus of the character described, a transverse carriage, a plurality of screed sections, a resilient mounting for each section, means for adjustably connecting each of said mountings with said carriage to depend therefrom, vibrating means on each section and power means carried by said carriage and operatively connected with each vibrating means.

3. In apparatus of the character described, a transverse carriage, a plurality of screed sections, a resilient mounting for each section, means for adjustably connecting each of said mountings with said carriage to depend therefrom, vibrating means on each section and resiliently mounted power means carried by said carriage and operatively connected with each vibrating means.

4. In apparatus of the character described, a transverse carriage, a plurality of screed sections, a resilient mounting for each section, a vibrator and shaft journalled on each section, flexible connections between said shafts, vibrating means on each section operable by the shaft thereon and means for driving one and thereby all of said shafts.

ROBERT WILLIAM BAILY.
